LINE-CASTING MACHINE

Arthur C. McGrath, Chicago, Ill., assignor of one-half to Melville Keim, Maple Lane, Highland Park, Ill.

Application January 13, 1936, Serial No. 58,961

2 Claims. (Cl. 22—2)

This invention relates to a line-casting machine and constitutes an improvement upon my patent, No. 1,314,006, which issued August 26, 1919.

5 An object of the invention is to provide means supported by the vise-jaw of the machine for casting stereotypes directly from the line-casting machine. A further object is to provide removable casting boxes which may be readily secured 10 in position to receive metal from the nozzle of the metal pot, the box being provided with means for aligning the opening of the box with the nozzle and the mold. A further object is to provide 15 means for maintaining the box at a proper temperature and at a substantially uniform temperature. Other specific objects and advantages will appear as the specification proceeds.

The invention is illustrated in preferred embodiments by the accompanying drawings, in 20 which—

Figure 1 is a vertical section through the mold disk and adjacent parts of a Linotype or line-casting machine, showing the mold in position to cooperate with my stereotype mold; Fig. 2, a 25 broken perspective front view of my removable casting box, the front plate having been removed; Fig. 3, a perspective view of the front plate of the casting box; Fig. 4, a transverse sectional view of the casting box with the front 30 plate thereof in position; Fig. 5, a modified form of the front plate, in which the front plate is provided with a heating element; Fig. 6, a broken 35 elevational view showing the casting box in position in the vise-jaw structure, and Fig. 7, a broken plan view of the casting box in position in the 40 vise-jaw structure the view being taken as indicated at line 7—7 of Fig. 6.

In the embodiment of the invention illustrated in Figs. 1—4, inclusive, the line-casting machine 45 illustrated is of the usual construction, and I have only shown so much of the machine as is necessary to understand the application of my invention.

In the drawings, the machine is provided, as 50 usual, with the slotted mold 2, in which the Linotype slugs or the like, as a rule, are cast. This mold is carried by the rotatable mold-carrying disk 3, which, when the casting operation takes place, brings the mold 2 into position opposite 55 the nozzle 4 of the metal pot 5. The matrix support 6 of the machine is of the usual construction, being provided with a transversely extending slot 7 in which the usual matrices are adapted to fit. The matrix-holder 6 is mounted on the 55 transversely extending arm 8 of the elevator,

the vertically extending arm 9 which is slidably mounted on the frame 1 and is raised and lowered by the lever 10, pivoted at 11, and raised into elevated position by means of a cam 12 operating upon a roller 13.

The main frame 1 of the machine supports near the top portion of the machine a vise-jaw structure 14 equipped with a pair of spaced jaws 50 and 51, shown more clearly in Figures 6 and 7 of the drawings. Also slidably mounted within 10 frame 1 is a vertical spacer-lifter rod 15 of the usual construction. The rod supports at its top a head 16.

My improved casting-box, which is shown in detail in Figs. 2, 3 and 4, is designated by the 15 numeral 17. As shown more clearly in Fig. 1, the box 17 is received within the space between the vise-jaw and the mold-block 2 and, when the head 16 of rod 15 is in raised position, it abuts the lower edge of box 17. The box 17 is 20 provided near its top with a laterally extending flange 18 which engages the top wall of the vise-jaw 14. The purpose of the flange 18 is to engage a stop-button, (not shown), the function of which is well-known in this type of machine. 25

While the casting-box is shown supported as a unit on the vise-jaw, one part of the box, if desired, may be secured to the matrix-support 6 so as to be raised by the elevator. In such a construction, I prefer to have the portion of the 30 box which is secured to the support 6 carry the resistance element and remain at rest in the vise-jaw.

My improved box 17, as shown more clearly 35 in Figs. 2, 3 and 4, consists of a rear-casing portion or block 19 and a front casing portion or plate 20. The casing 19 provides a hollow compartment receiving a pair of insulation sheets 21 between which are wound electric resistance wires 22. The wires 22, as shown more clearly 40 in Fig. 2, pass through the insulated case of a thermostat 23, and the current passing through the wires 22 is controlled by the thermostat. The thermostat construction, being well-known, will not be described in detail. It is sufficient to state 45 that the thermostat breaks the circuit when the temperature exceeds 400° or 450° F. It will be understood that the thermostat may be set to break the circuit at lower temperatures, if desired. The thermostat, by interrupting the current at certain temperatures and closing the circuit when the temperatures drop, thus maintains 50 a fairly uniform temperature. The casing 19 provides near its top rear side a chamber 24 in which the thermostat element 23 is housed. 55

- Above the box-casing 19 is supported a hollow metal conduit 25 through which the wires 35 leading to the heating element 22 are housed. The housing 25 prevents injury to the wires 35
- 5 when the housing is engaged by the depending matrix-holder 6, as shown more clearly in Fig. 1. The heating chamber is closed on its front side by a removable plate 26. As shown more clearly in Fig. 2, I prefer to provide the casing 10 19 with laterally extending locking lugs 27.
- Secured to the bottom of casing 19 is a forwardly extending platform 28 having an upturned terminal flange 29.
- The front plate 20 has a lower portion adapted 15 to be received within the space provided by the platform 28 and the edge 29. Preferably the front plate is recessed on its rear side to provide a chamber 30 between the front plate and the closure plate 26 of the rear casing member 19.
- 20 The upper portion of plate 20 is provided with a transverse slot 31 through which the metal passes to the interior of chamber 30. Toward the bottom portion of plate 20 is formed a rearwardly rib 32 which is adapted to engage the lower edge 25 of the mold-block 2 and thus maintain the slot 31 in alignment with the nozzle 4 and the aperture in the mold 2. Integrally formed with the front plate 20 are rearwardly and laterally extending lugs 33 which are brought into alignment above and on lugs 27. The lugs 27, resting 30 securely on a portion 52 of the vise-jaw 14, and the lugs 33 lying on top of the lugs 27, hold the plate 20 in such a position that the lug 32 is in position to engage the lower portion of the mold 35 2 as the machine performs its usual function.

Operation

In the operation of the device, the front plate 20 is placed in position against the plate 26 of casing 19, the lower portion of the plate 20 being received behind the flange 29, as shown more 40 clearly in Fig. 4. The laterally extending lugs 27 and 33 are thus brought into alignment. The casting-box may then be inserted within the space between the vise-jaw 14 and the jaws carried by 45 the vise-jaw, as shown more clearly in Fig. 1. In this position, the laterally extending lugs 33 and 27 extend behind and interlock with the spaced jaws 50 and 51 of the vise-jaw 14. Also the laterally extending lugs 27 rest upon portions 52 of 50 the jaws. At the same time, the flange 18 rests against the top wall of vise-jaw 14. When the box is first inserted, the mold-disk wheel 3 is in retracted position and when it is moved forward, as in the usual operation of the machine, the flange 32 of the front plate 20 extends below 55 the lower edge of the mold-block 2, thus aligning the metal inlet 34 with the passage through mold-block 2 communicating with nozzle 4. To insure perfect alignment, the head 16 as it is raised by the spacer-lifter 15, engages the bottom of box 17 so as to press the rib 32 tightly against the bottom edge of mold-block 2.

At the time the casting box 17 is placed in position, the current is turned on and the electric heating element within the box rapidly brings the temperature of the box up to the desired temperature for the metal used. The temperature should be sufficiently high to cause the metal to flow evenly over the stereotype mat which is, of course, held within chamber 30 of the casting-box. 60

70 At the same time the temperature of the box

should be sufficiently low to cause the metal to harden after it has covered the front surface of the mat. I have found temperatures between 400° and 450° F. suitable, although lower temperatures may be satisfactory. The thermostat is so set as to break the current and prevent a temperature rise above the selected temperature.

Metal is then forced from the metal pot 5 through nozzle 4, the aligned opening in block 2 and into the interior of chamber 30 so as to fill 10 the chamber in front of the mat and to flow freely over the face of the mat. The heated box causes the metal to flow readily into the corners and interstices of the mat surface and to reproduce the surface accurately as the metal hardens. 15

20 After the cast has hardened, the mold-carrying disk 3 recedes to its normal position and at the same time the elevator arm 9 is automatically raised to its normal position. As in the well-known operation of the machine, the disk 3 rotates and the slug within the metal passage in mold 2 is ejected. The casting-box may then be opened and the casting removed. By supporting the casting-box within the vise-jaw, it is easy to provide electrical connections with the box because of the absence of movement of the box when thus located.

In the modified form of the invention illustrated in Fig. 5, the front plate 20a is provided with a heating chamber engaging heating elements 22a between insulation strips 24a. The compartment is closed on the rear side by a closure plate 34. The plate 20a is, in other respects, identical with plate 20, being provided with similar locking lugs 33a. 35

While in the foregoing illustrations, I have set forth certain embodiments of the invention, it will be obvious that the invention can be practiced in widely differing embodiments; and it is obvious that changes and alterations can be made without departing from the spirit of my invention. 40

The foregoing detailed description has been given for clearness of understanding only, and no unnecessary limitations should be understood therefrom, but the appended claims should be construed as broadly as permissible, in view of the prior art.

I claim:

1. A casting box adapted for use with a line-casting machine, comprising: a rear casing member having at its bottom a forwardly extending platform, said member being equipped with means for locking said member to the machine, and a slotted front cover having edges adapted to engage the edges of a paper matrix placed against said rear casing member to form a chamber adjacent the matrix, said cover being equipped with means for engaging said machine to hold the cover against said platform. 50

2. A casting box adapted for use with a line-casting machine, comprising: a rear casing member having at its bottom a forwardly extending platform, said member being equipped with means for locking said member to the machine, and a slotted front cover resting on said platform and spaced from said rear casing member, said cover being adapted to slide along said platform to vary the spacing between said cover and said rear casing member. 55

ARTHUR C. MCGRATH. 70
